BADGE OR SIMILAR ARTICLE

Charles Warren Mayer, 129 S. Prospect, Rockford, Ill.

Filed Dec. 28, 1962, Ser. No. 72,977

Term of patent 14 years

(Cl. D29—11)

FIGURE 1 is a plan view of a badge showing my design.
FIGURE 2 is a top view thereof.

FIGURE 3 is a side view thereof.

FIGURE 4 is a rear view thereof on a reduced scale.

The essential features of my design reside in the full line showings on the drawing, and comprise an open triangular frame having two relatively thick sides and one relatively thin side, a square and compass connected to one inner edge thereof, a pair of crossed batons or swords each overlying two sides of the triangle, and a trowel centered on the crossing and pointing to the third side of the triangle, all as shown.

I claim:

The ornamental design for a badge or similar article, substantially as shown and described.
